Primary Examiner — Christian P. McLean*Assistant Examiner* — Jessica Lynn Devilbiss(74) *Attorney, Agent, or Firm* — Bond, Schoeneck & King, PLLC(57) **CLAIM**

The ornamental design for a tonneau cover as shown and described.

DESCRIPTION

FIG. 1 is a perspective view showing a first embodiment of a tonneau cover;

FIG. 2 is a front elevational view of the tonneau cover of FIG. 1;

FIG. 3 is a rear elevational view of the tonneau cover of FIG. 1;

FIG. 4 is a right side elevational view of the tonneau cover of FIG. 1;

FIG. 5 is a left side elevational view of the tonneau cover of FIG. 1;

FIG. 6 is a top plan view of the tonneau cover of FIG. 1; and, FIG. 7 is a bottom plan view of the tonneau cover of FIG. 1.

The broken lines illustrate portions of the tonneau cover that form no part of the claimed design.
